UNITED STATES PATENT OFFICE.

RAYMOND C. PENFIELD, OF NEW YORK, N. Y.

APPARATUS FOR HANDLING BRICKS IN STACKED UNITS.

1,205,562.

Specification of Letters Patent. Patented Nov. 21, 1916.

Application filed January 12, 1912. Serial No. 670,825.

To all whom it may concern:

Be it known that I, RAYMOND C. PENFIELD, a citizen of the United States, and resident of New York city, county and State 5 of New York, have invented an Improvement in Apparatus for Handling Bricks in Stacked Units, of which the following description, in connection with the accompanying drawings, is a specification, like letters 10 on the drawings representing like parts.

This invention relates to apparatus for lifting and transferring bricks in stacked units, of the type having a series of spaced apart, parallel fingers adapted to enter passages in the lower part of the brick units, with provision to laterally grip the bottom brick lines and lift them along with the rest of the stack, the apparatus being adapted to deposit the stacked units and be withdrawn without disturbing the stacked formation. Apparatus of this general type is shown in my prior Patent No. 999,519, issued August 1, 1911, and the present invention may be considered in a general way as 20 an improvement over the mechanism of said patent. The present machine, in common with that shown in said patent, is adapted to engage and lift units of any length or height or depth within considerable limits, 25 the illustrative machine shown having a maximum capacity for eight bricks long, four bricks deep, and ten bricks in height, including the basic layers.

One of the principal objects of the present invention is to provide a relative arrangement of the parts to which the lifting impulse is applied relative to the parts which engage the brick stack, so that they are substantially balanced with reference to 35 a vertical slide bearing which these parts have on each other, so that the parts have a direct vertical movement, and a perfect balancing of the machine either with or without load is effected.

A further object of the invention is to provide an improved arrangement of compression springs between the movable parts adapted to have an initial compression sufficient to keep the movable parts in fixed 40 relation when there is no load upon the machine and to yield under compression when load is brought upon the springs to permit the operation of the lateral clamping devices.

Another object is to provide an improved construction of swiveling device adapted for

use in connection with the lifting mechanism to permit movement thereof as required for proper positioning in setting the brick units, while keeping the stack level 60 and evenly supported; the preferred embodiment shown for effecting this result including a four-hook crane and a four-hook swivel in conjunction with a four-hook suspension of the setter. This feature of providing a four-point suspension capable of 65 swiveling action is of particular importance in a setter of the type herein shown, where large loads are to be handled, and therefore where means is necessary for maintaining 70 the entire carrying frame steady and level when loaded, irrespective of the amount of load carried by the frame. Heretofore it has been customary in setters of this type to depend solely upon the construction of 75 the lifting apparatus and of the balancing bars and springs therein to maintain the setter substantially level so that it may be lifted from a single point of suspension, but this type of setter was necessarily limited 80 to carrying small loads of brick, and was not applicable to carrying large loads, for example, an entire wagon load, without a plurality of points of suspension insuring 85 the substantially level position of the setter 90 at all times.

A still further object is to provide an improved manner of connection from the bail to the lifting levers and from the levers to the equalizer beam, so that all these parts 95 are free for self-adjusting movement to insure a uniform distribution of pressure upon the basic layers of bricks, thus enabling the machine to take care of any variations in the thickness of the bricks and making it certain that all bricks in the basic layer shall 100 be lifted together and in undisturbed relation.

The above and other objects of the invention having to do with improved structural features will be better understood from the following detailed description, taken in connection with the accompanying drawings, and will be thereafter pointed out in the appended claims.

Referring to the drawings, Figure 1 is a rear elevation of one form of my invention. Fig. 2 is a plan view on a smaller scale, showing the parts of the swivel support. Fig. 3 is a side elevation, partly broken away. Fig. 4 is a perspective view of a lifting finger. Fig. 5 is a fragmentary sec-

tion of the lifting finger, showing the means for operating the clamping plates. Fig. 6 is a rear elevation, partly in section, showing a modified form of the invention, and Fig. 7 is a side elevation, partly broken away, of this form.

In the illustrative embodiment of the invention shown, and referring first to Figs. 1 and 3, a base bar or frame 1 is employed of a length corresponding to that of the brick units to be handled, and to this bar are fixed a series of horizontal, parallel, spaced apart, lifting fingers 2, the length of these fingers being determined by the depth of the units or combinations of units which it is desired to handle at a time. The base bar or frame 1 has equally spaced from its center and at some distance therefrom, uprights 3 adapted to serve as guiding slide-ways for the vertically moving bails 4 by which the mechanism is lifted. The uprights 3 at either side are each formed of a pair of bars 5, 6 between which a depending projection from the bail 4 is guided. These guiding plates 5, 6 are held rigid in upright position by braces 7 at either side extending diagonally downward and bolted to lugs on the base frame, as seen at 8. Each bail 4 is shown as provided with anti-friction rollers 9 at its top, front and back for engaging the portions of the uprights 3, and its depending extension 10 is provided with similar rollers 11, 12 for engagement with the back sides of said uprights. Each bail 4 has a longer portion 13 extending out from the front side of the uprights, *i. e.*, the side from which the lifting fingers 2 project, and a shorter portion 14 projecting out from the opposite or rear side. The base frame 1 and the bails 4 constitute the two relatively movable portions of the mechanism, the relative movement between which effects the operation of the clamping elements, and between these relatively inmovable parts sets of compression springs 15 at either side are interposed. To furnish a backing for these springs, plates 16 are bolted to the braces 7 and thus made rigid with the base frame and in these adjusting bolts 17 are threaded and adapted to hold at their lower ends backing heads 18 for the springs, in adjusted position. These adjusting bolts may be locked in the desired adjusted position by usual lock nuts 19. The short rear extensions 14 of the bails 4 have each pivoted thereto depending link rods 20, which are connected at their lower ends to an evener bar 21. This bar is pivotally connected at 22 to a plate or block 23, which, in turn, is pivotally connected at 24, 25 to the ends of levers 26, 27, having their pivot fulcrums at 28, 29 in brackets formed rigid with the base framework. These levers 26, 27 are provided immediate of their length with laterally extending seating heads 30 for the lower

ends of the series of springs 15, there being guide rods 31 extending upward from these seats and slidable through the heads 18. The levers 26, 27 have also connected thereto, intermediate of their length and shown as between the seats 30 and the lifting pivots 24, 25, straps 32 engaged with an equalizer beam 33. As seen in Fig. 3, the lower ends of these straps are flared out and fitted over the equalizer beam which may be, as shown, an I-bar. The equalizer beam 33 extends substantially the length of the machine back of the rear ends of the fingers 2, and furnishes a seat for a series of springs 34 fitted around sets of rods 35, slidably guided through the beam 33 and having heads 36 at their upper ends engaging the tops of said springs. A set of rods 35 is provided for coöperation with each finger 2, the number of rods in the set corresponding to the number of grip plates which each finger carries, and hence to the number of bricks in depth which the machine is adapted to lift. Each set of rods 35 for the respective fingers is pivotally connected to a set of bell crank levers 37 fulcrumed at 38, one behind the other, as shown, in a rearward extension 39 of the base framework and connected at their other, and as shown, shorter, ends, each to one of the rods of a set 40. These sets of rods 40 extend into the respective fingers 2 along lengthwise recesses 41 formed in one side of the lower part of said fingers. Each finger is also recessed at intervals along its length, as seen at 42, to provide mountings 100 and seats for the grip plates 43. These grip plates are pivotally mounted, as at 44, on lever arms 45 mounted on vertical pivots 46 in the fingers and having rigidly connected therewith, other, and as shown shorter, lever arms 47 with which the operating rods 40 are pivotally connected, as seen at 48. The grip plates 43 are of some little length, as shown, to afford adequate gripping surfaces, and when in drawn-in or collapsed position are housed in cut-out portions 49 in the front sides of the fingers. In their expanded position as they swing out on the lever arms 45 as the rods 40 are drawn outward, and project out from the sides of the fingers, they press upon the sides of the basic lines and by the frictional engagement thus created effect the lifting thereof along with the rest of the unit. By reason of the arrangement of the evener bar 21 with the central movable connections 22, 24, 25, the lifting impulse, though it may be unequal on the bails at the two sides of the apparatus, is rendered even and uniform in its application to the equalizing beam 33. The springs 34 interposed between the equalizer beam and the grip plate operating rods 40 accommodate inequalities in the several bricks, so that each grip plate engages a brick with yielding equalized pressure and 130

thus the entire basic layers are lifted along with the rest of the unit without possibility of disarrangement. The compression springs 15 are made strong, so as to only 5 yield appreciably under the strain exerted in lifting a brick load and they are adjusted so as to be initially under some little compression and thus keep the relatively movable bail and base frame and parts carried 10 thereby in normally fixed relation.

The form of the invention shown in Figs. 6 and 7 is generally similar to that just described, and corresponding parts differing slightly in structure therefrom, but the 15 same in function, are designated by corresponding characters primed. In this form the evener bar 21' is pivotally connected by a link 50 to a second bar 51 centrally thereof, the bar 51 having link connections 52 20 at its ends to the lever 27'.

In both forms of the invention shown, the apparatus as described is supported in depending relation to an overhead swiveling device by links 53, pivoted to the bails at 25 their rearward extensions, and like links 54, pivoted to the forward bail extensions, these connections being at points selected with reference to an even distribution of the lift when the machine is loaded. The upper 30 ends of links 53, 54 are pivotally connected to T-bars 55, there being two of these bars spaced apart over the respective bails. The bars 55 are fixed to a peripheral flange 56 extending from an outer ring 57 which is 35 provided with an inwardly extending runway 58 for anti-friction balls or rollers 59. An inner ring 60 is provided with a runway 61 coöoperating to hold the balls 59 in 40 place, and this ring has fixed to its top T-bars 62 shown as arranged in spaced apart parallelism. The end portions of these bars extending without the rings have fixed underneath the same other T-bars 63, forming therewith a lifting frame, and at the ends of 45 these latter bars are secured lifting straps 64, adapted to be engaged by the hooks of a crane, or other transporting apparatus. It is thus to be observed that the lifting connection from the bails 4 is effected 50 through the four links composed of the pairs 53, 54, which links are symmetrically disposed with reference to the center of the load and that the lifting connection from the crane to the turntable provided by the 55 two coöoperative rings 57, 60, is likewise through four spaced apart hook connections which are also symmetrically disposed about the load center.

I consider the construction whereby the 60 relative guided sliding movement between the bails and the base frame is substantially coincident with the load center to be an especially important feature of the invention, since thereby the relatively movable parts operate in what may be termed 65

the axis of lift, and a substantially perfect balancing of all parts of the machine from the crane connections to the load is effected; this construction also enables an easier and more certain operation of the relatively 70 movable elements, since the binding tendency between these is reduced to a minimum. The construction and arrangement whereby the bail is attached to the equalizer beam and hence to the grip plates through 75 a system of movably pivoted levers, including an evener, is also an important improvement, since thereby a uniform distribution of pressure is brought upon all parts of the basic brick layers, thus making certain the 80 lifting of the entire basic layers in undisturbed relation to the rest of the stack and taking care of any variations in the thickness of the bricks.

The four-point suspension and the turntable which I have shown and described, constituting automatic means to raise and maintain the entire brick setting frame steady and level at all times during operation, when loaded, and with varying successive loads of brick, enabling a relatively large stack of brick to be handled, is of particular importance. Such construction also enables the entire load to be swung around and fixed in any desired position 95 and to be stacked evenly when swung to new position and released from the setter. I believe it to be a distinct novelty in this art to provide swiveling means having a plurality of lifting points symmetrically arranged, and therefore wish to claim the same broadly.

I am aware that various of the features of the construction can be modified in many respects without departing from the spirit 105 of the invention, and I therefore do not desire to be limited as to these, or in any way, except as set forth in the appended claims.

Having described my invention, what I claim as new and desire to secure by Letters 110 Patent is:

1. An apparatus of the kind described, comprising a base frame having fingers extending at one side thereof with brick clamps, spaced apart bails slidably guided 115 on said base frame extending out over said fingers and also at the other side of the line of slidable engagement with the base frame, said bails being connected to operate said brick clamps, and also having springs positioned to balance the parts along the lines of slidable engagement when under load, an overhead lifting frame, and links connecting said lifting frame to said bails near the ends thereof and constituting a substantially balanced suspension for the apparatus under load.

2. An apparatus of the kind described, comprising a base frame having lifting fingers with brick clamps, spaced apart bails 130

slidably guided on said base frame connected to operate said brick clamps and having provision for balancing along the line of slidable engagement with the base frame 5 under load, and lifting means including a plural link connection to said bails symmetrically disposed with reference to the axis of lift.

3. An apparatus of the kind described, 10 comprising a base frame having lifting fingers extending at one side thereof with brick clamps, bails in slidable engagement with said base frame with connections for operating said brick clamps, a lifting frame having plural link connections with said bails, and a swivel connecting said lifting frame with a crane or the like, said swivel and said link connections being arranged symmetrically with reference to the axis of lift when 15 the machine is loaded.

4. An apparatus of the kind described, comprising an upper support adapted for engagement by a crane or the like, a lifting frame having a turn-table connection with 20 said upper support, bails having link connections with said lifting frame, said link connections and said turn-table being symmetrically disposed with reference to the axis of lift, a base frame in slidably guided 25 engagement with said bails having laterally extending fingers with brick clamps carried thereby, connections from said bails to operate said clamps, and a spring connection between the bails and said base frame adapt- 30 ed to yield under load for the purpose stated.

5. An apparatus of the kind described, comprising a base frame having lifting fingers extending laterally therefrom with brick clamps, spaced apart bails slidably 40 guided on the base frame, connections from said bails for operating said clamps and for lifting the load, including levers pivoted to either side of the frame connected with the clamps, and an evener connected centrally 45 to the free ends of said levers and at its ends to said bails for distributing lifting strains.

6. An apparatus of the kind described, comprising a base frame having a series of laterally extending fingers with brick 50 clamps, spaced apart bails in slidable engagement with said base frame and having connections to operate said clamps, including an equalizer beam with individual yielding connections to the respective clamps, and 55 lever connections from said beam to the bails with an evener interposed therein.

7. An apparatus of the kind described, comprising a double lifting frame, one frame having a series of laterally extending 60 fingers with brick clamps adapted to apply

a lifting grip to the bottom row of bricks while still in contact with the ground, a second frame constructed and arranged to slide upon said finger-carrying frame, and to actuate the brick clamping means on said first 65 frame, yielding connections between said brick clamping means and said sliding frame, in combination with normally vertical lifting links applied at a plurality of 70 points on the sliding frame whereby movement of the latter frame operates the brick clamping means.

8. In a brick handling machine, the combination of a lifting frame having a series of freely projecting fingers, a second frame 75 slidable upon the lifting frame, a plurality of normally vertical lifting links adapted to raise the second frame and slide the same upon said lifting frame while maintaining both in parallelism, brick-clamping means 80 coöperating with said fingers and operated by the relative sliding movement of said two frames, and balancing springs connecting said two frames and modifying the operative movement of said frames and clamping 85 means.

9. In a brick handling machine, the combination of a lifting frame having a series of freely projecting fingers, a second frame sliding upon the lifting frame, a plurality of 90 normally vertical lifting links adapted to raise the second frame and slide the same upon said lifting frame while maintaining both in parallelism, brick clamps operatively related to said fingers, means connecting said 95 clamps with the sliding frame, including yielding devices, and balancing springs connecting said two frames.

10. In a brick handling machine, the combination of a lifting frame having a series 100 of freely projecting fingers, a second frame slidable upon the lifting frame, a plurality of normally vertical lifting links adapted to raise the second frame and slide the same upon said lifting frame while maintaining 105 both in parallelism, brick-clamps operatively related to said fingers, means connecting said clamps with the sliding frame, including yielding devices, and balancing springs between the lifting frame and the 110 sliding frame and having provision for being operated with said connecting means.

In testimony whereof, I have signed my name to this specification, in the presence of two subscribing witnesses.
